TUBULAR LINK CONSTRUCTION

Saul Ritter, New York, N. Y.

Application April 16, 1946, Serial No. 662,544

5 Claims. (Cl. 59—79)

1

This invention relates to an expandible band of the type constructed with slideable telescopic links to be used as a bracelet or wrist watch strap.

An object of the invention is to provide a slideable link type band with the links thereof so constructed and arranged as to resist distortion under abnormal stress during use.

Other objects and advantages of the invention will be evident from the following description together with the drawing in which

Fig. 1 is a perspective view showing a band constructed in accordance with the present invention as applied to a watch;

Fig. 2 is a top plan view of several connected links of a band with the links in extended positions;

Fig. 3 is a bottom view of the links shown in Fig. 2;

Fig. 4 is an enlarged side elevational view of the several links in expanded positions.

Fig. 5 is a perspective view of the outer section of a link;

Fig. 6 is a perspective view of an inner section of a link.

Fig. 7 shows a developed metallic blank ready to be shaped to provide an outer link section, and

Fig. 8 is a perspective view of an outer link section partly formed prior to the closure of a portion of the bottom wall for interlocking with another portion thereof.

The present invention as shown in the drawings is directed to a band or bracelet, each link of which consists of two tubular members or sections in concentric or telescopic relation and relatively slideable along a common longitudinal axis.

For practical and economic reasons each tubular member or section is formed from a sheet metal blank into tubular shape with the contacting edges of the blank resulting in a seam running longitudinally of the member.

The relative movement of each tubular member, with respect to the other member, when assembled to provide a band, results in an expansion or contraction of the band. For the purpose of holding the members contracted and to thereby contract the band or strap, it is the practice to provide each link with a spring element which tensionally engages and normally holds the members contracted or in concentric relation.

It will be understood that a band of the present type although in the nature of an article of jewelry is subject to relatively rough treatment. The necessity for frequent expansion and contraction of the bracelet when putting it on or taking it off from the wrist subjects the links not

2

only to a uni-directional stress as when normally expanded or contracted, but the outer tubular member is subjected to severe lateral stress as when the strap or band is drawn over the hand. During this operation the band is not only expanded but during expansion a force is also applied which tends to move one member of an expanded link out of alignment with the other member.

10 The inner tubular member or section being slideable within the outer member holds its shape, but any lateral strain causes the inner member to exert a force against the side walls of the outer member. This force is in some cases relatively great since when the inner member is expanded a certain amount of leverage is created resulting in an opening of the seam of the outer member or section. This unavoidable tendency toward distortion causes the edges of the sheet metal blank, from which the member or section is formed, to separate and open the seam of the outer tubular member or section. Obviously such distortion of a link destroys the usefulness of the band.

15 25 The present invention provides a link structure of the above described tubular type formed from a sheet metal blank and avoids the opening of the seam under stress, by means of a simple and effective mechanical interlocking construction.

30 The present invention may be practiced with any of the numerous tubular link construction bands or bracelets, an example of which is shown in the drawing. As illustrated an expandible band 10 is shown having its ends attached to a watch 11 in the usual manner, as for example, with the well known spring-bar connector.

35 The strap or band is, in accordance with the present invention, comprised of a plurality of telescopic links pivotally connected for relatively limited movement as will be described. Each link or link assembly 14 consists of two members or sections in concentric or telescopic relation and includes an outer member 15 and an inner member 16. The member 16 is so formed and dimensioned as to have a slideable fit for endwise movement in the outer member 15. The inner member is attached to move almost entirely within the outer member as when the band is contracted or moved almost entirely out from the outer member 50 as when the band is expanded.

40 As shown, each tubular member or section is fabricated from a sheet metal blank. The outer member 15 has a top wall 20, bottom wall 21 and side walls 22 and 24 which provide a tubular section of substantially rectangular formation in

transverse cross section when formed from the blank as shown in Figs. 7 and 8.

The ends 25 and side walls 22 and 24 extend to provide a pair of ears having bearing apertures to receive a pintle 27 thereby providing a hinge connection in cooperation with apertured ears 28 and 29 of the inner tubular member 16 of adjacent link assembly 14.

The inner tubular member has a top wall 33, bottom wall 34 and side walls 35 and 36. The member 16 is, as above pointed out so shaped and dimensioned as to slidably fit the outer member 15 providing the telescopic assembly arranged to expand and contract producing an expandable band when the link assemblies are hingedly connected.

For the purpose of holding the tubular members or sections in operative relation the side walls of the inner member 16 are provided with channels 37 to receive lugs 38 formed on the side walls of the outer member 15. The channels are terminated at one end by a wall 39 to limit the outward movement of the inner member 16.

The tubular members are held in normal contracted relation by a spring 41. One end of the spring may, as shown, be attached to a hook element 42 integral with the bottom wall of the tubular member 15. The opposite end of the spring 41 may, as shown, be attached to a hook element 43 integral with the bottom wall of tubular member 16. The spring 41 which is normally contracted holds the tubular members in contracted relation.

An expandable band of the present character is sold in great quantities and although of relatively intricate and complicated construction, it must be manufactured at relatively low cost. It has been found desirable from a practical standpoint, in meeting the demands of high speed production to form each of the tubular members from sheet metal blank so fabricated that a seam extends longitudinally of the bottom wall of each tubular member. As for example, the seam 44 formed in the bottom wall of member 15 and the seam 45 in the bottom wall of the member 16.

As shown in Figs. 2 to 4, when the members 15 and 16 are in their extended or expanded positions the member 16 is disposed with its end 46 extending a relatively short distance into member 15. When in this expanded position the member 16 acts as a lever and any lateral force as indicated by arrow x, Fig. 3, applied to the member 16, as for example, at the hinge connection 41, serves to exert an amplified force to a side wall of the member 15. A repetition of the application of this force causes a separation of the edges 48 and 49 of the seam 44. For the purpose of preventing an opening of the seam 44 the edge 48 thereof is provided with an extension 51 to be received in a complimentary notch 52 formed in edge 49. This extension and notch may be of any suitable interlocking construction, as for example, a so-called dovetail joint. This joint or lock is disposed relatively close to an end of member 15 so as to lie beneath the end 46 of a member 16 when extended. By reason of this interlocking construction edges 48 and 49 are maintained in contacting relation and resist separation due to force applied by lateral stresses imparted to member 16 when in its extended position.

The locking means shown and disclosed lends itself to high speed fabrication of the links in that the blanks may be punched with the co-

operating locking formation and may be automatically shaped to the required tubular formation bringing the edges of the blank automatically into interlocking relation by a single operation.

An expandable band of the type above described may be subjected to severe and continuous use without distortion and provides a more durable and practical article as desired in this class of merchandise.

Although a preferred embodiment of the invention is shown and described herein, it will be understood that modifications may be made therein without departing from the spirit and scope of the invention as set forth in the appended claims.

What is claimed is:

1. An expandable band comprising a plurality of telescopic links, each of said links including an outer member and an inner member, said inner member disposed in said outer member so as to be slidable from a position wherein it is substantially fully received within the outer member to a position wherein a major portion of said inner member extends from one end of said outer member, said outer member being formed from a sheet metal blank to tubular form with the opposite edges of the blank forming a longitudinal seam in a wall of said outer member, an extension adjacent 25 to said end of said outer member and integral with one of said edges, said other edge having an aperture to receive said extension to interlock said edges.

2. An expandable band comprising a plurality 35 of telescopic links each of said links including an outer and an inner member, the outer member being formed from a sheet metal blank to tubular form with opposite edges of the blank forming a longitudinal seam in the bottom wall of said outer member, one end of said outer member having registered apertures in side walls thereof, a hinge pin disposed in said apertures to pivotally connect said outer member to an inner member and serving to hold the edges of the seam at one end 40 thereof against separation and means along the seam for interlocking the edges thereof against separation at the other end thereof.

3. An expandable band comprising a plurality 50 of telescopic links each of said links including an outer and an inner tubular member, the outer member being formed from a sheet metal blank with opposite edges of the blank forming a longitudinal seam in the bottom wall of said outer member, one end of said outer member having registered apertures in side walls thereof, a hinge pin disposed in said apertures to pivotally connect said outer member to an inner member and serving to hold the edges of the seam at one end 55 thereof against separation, a projection integral with one edge of said seam and an aperture on the other edge of said seam to receive said projection to interlock the seam against separation at the other end thereof.

4. A link unit for an expandable band comprising 60 inner and outer tubular members disposed in telescopic relation, the outer member being formed from a sheet metal blank with opposite edges of the blank forming a longitudinal seam in the bottom wall of said outer member, one end 65 of said outer member having registered apertures in side walls thereof to receive a hinge pin for pivotally connecting one end of an inner member to said end of said outer member and thereby serving to hold the edges of said seam at one 70 end thereof against separation and means along 75

the seam for interlocking the edges thereof against separation at the other end thereof.

5. A link unit for an expansible band comprising inner and outer tubular members disposed in telescopic relation, the outer member being formed from a sheet metal blank to tubular form with opposite edges of the blank forming a longitudinal seam in the bottom wall of said outer member, one end of said outer member having registered apertures in side walls thereof to receive a hinge pin for pivotally connecting one end of an inner member to said end of said outer member and to hold the edges of said seam at one end thereof against separation and a projection to provide a tenon integral with one of said edges, 15

the other of said edges having an indenture to receive said tenon and interlock the edges of said seam against separation at the other end thereof.
